US0D1037936S

(12) **United States Design Patent** (10) Patent No.: **US D1,037,936 S**
(45) Date of Patent: ** Aug. 6, 2024

(54) **BICYCLE FRAME**

(71) Applicant: **DECATHLON**, Villeneuve D'Ascq (FR)

(72) Inventor: **Cyrille Rouffiat**, Villeneuve D'Ascq (FR)

(73) Assignee: **DECATHLON**, Villeneuve d'Ascq (FR)

(**) Term: **15 Years**

(21) Appl. No.: **29/882,714**

(22) Filed: **Jan. 18, 2023**

(30) **Foreign Application Priority Data**

Jul. 28, 2022 (EM) 009099773-0002

(51) **LOC (14) Cl.** **12-11**

(52) **U.S. Cl.**

USPC **D12/111**

(58) **Field of Classification Search**

USPC D12/111, 114, 115, 117; D21/412, 414, D21/419, 423, 425, 426, 427, 431, 432
